UNITED STATES PATENT OFFICE.

WILLIAM C. CUTLER, OF GLENDALE, CALIFORNIA, ASSIGNOR TO ISABELLA M. CUTLER,
OF GLENDALE, CALIFORNIA.

ROTARY SELECTING MECHANISM FOR VENDING MACHINES.

Application filed October 13, 1925. Serial No. 62,253.

The present invention relates to selective vending machines and has for its principal object the provision of a machine in which there is provided a plurality of article holding spaces, arranged to be seen by the operator of the machine, from any selected one of which holders the contents may be had by proper operation of the machine.

Another object of the invention is to provide a machine of the above character, including several article holders, in which machine only one coin chute and operating mechanism is required.

Another object of the invention is to provide for employing simple and visible selecting means.

Still another object of the invention is to provide a machine in which the article holders may be radially arranged to provide a compact machine of both minimum height and breadth, in which machine selective vending of the contents is accomplished without collectively moving or disturbing the contained articles.

Another object of the invention is to provide a machine which is readily refilled.

Still another object of the invention is to provide a coin controlled vending machine in which the coin controlled mechanism is readily removed and replaced with another or repaired, without disturbing the contents of the machine.

Still other objects and advantages of my invention will appear hereinafter.

I have illustrated my invention by the accompanying drawings, in which—

Figure 1 is a front view, on a small scale, of one practical embodiment of my invention.

Figure 2 is a view in vertical section, on a larger scale, as seen on a line 2—2 of Figure 1.

Figure 3 is a view in section on a line 3—3 of Figure 2, on the same scale as Figure 1.

More specifically, in carrying out my invention in the embodiment illustrated I provide a casing 6 having a rear wall 7 and a complete annular wall 8 spaced forwardly of the rear wall to provide the space 9. A front wall 10 is provided which is similar to the back wall except that it is fitted with a circular glass door 11 thru which the article holding portion of the machine is

visible and thru which the machine may be filled. The annular walls is shown integral with the front wall and includes integral walls 12 which are directed radially inwardly to provide a plurality of article holding pockets 12^a open at the front as at 14 and open at the rear as at 15. The inner ends of opposed walls are bent inwardly as at 16 to retain a package or article such as 17. Obviously an article may be inserted in a holder thru the front open end and may be removed from the rear open end. The rear wall continues well below the lowermost part of the annular wall and curves forward as at 18 to provide an article discharging chute 19. Any article which is forced out of a holder thru the rear open end will fall into the chute from which it may be obtained. Where boxes of a constant size are employed said boxes should be a friction fit in the holder 3 so that they cannot be vibrated or otherwise moved therewithout applying appreciable force to the forward ends thereof.

The door of the casing is provided with radial ribs 22 connecting with an outer annular frame 23. Said ribs support a central casing 24 which contains a coin released lock (not shown). The casing wall is provided with a coin slot 25. A push rod 26 passes thru the casing and has its inner end within the interior of the machine while its outer end terminates in a push button 27. Coin controlled locks and the like are well understood and it is not necessary to herein describe any specific form, it being understood that the push rod cannot be forced inwardly unless a coin is deposited in the coin slot, and when the rod has once been pushed in and allowed to return, it cannot be moved inwardly again until another coin is deposited.

The portion of the rod which is within the article holding casing is provided with a single radially projecting finger 29 adapted to move inwardly of the machine with the push rod to force an article out of its holder into the dotted line position in which such article is shown in Figure 2.

In conformance with a salient feature of this invention, the article holders are stationary while the rod is revoluble without interference with the coin controlled lock. In other words, the rod may be revolved

regardless of whether or not a coin is inserted in the slot. The lock includes a movable member 30 arranged to be abutted by a collar 31 carried by the push rod. This member is normally in the dotted line position shown in Figure 2, but when a coin is inserted in the mechanism it is moved to the position shown, permitting the rod to be pushed inwardly of the machine.

- 10 10 To operate the machine, the rod is turned until it is alined with, or points to, the desired article. The articles are all visible thru the glass door, there being no articles immediately behind the ribs. The finger 15 serves as a visible indicator, and the nature of the article contained in an article holder may be indicated directly on the visible surface of the box. When the finger is alined with the desired article a coin is inserted in 20 the slot. Then the rod is pushed inwardly and the finger moves between the walls of an article holder and forces the article out rearwardly. The article then gravitates into the chute.
- 25 25 To refill the machine or to replenish any holder the front door is swung open on its hinge 32. The finger, rod, and coin controlled rod-lock are all carried by the door. If the operating parts become clogged or 30 otherwise damaged a new door is very readily installed in place of the old one.

While I have shown and described a specific embodiment of my invention I do not limit myself to any specific construction or arrangement of parts and may alter same as I desire or as occasion requires, without enlarging the scope of my invention within the appended claims.

I claim:

1. In a selective vending machine, a casing, a plurality of radially arranged article holders encompassing a central coaxial space, a push rod extended thru said casing movable thru said space; said push rod being revoluble and said holders being open in 45 the rear, a finger extended radially from said rod, said finger arranged to move with said rod to eject the contents of any holder with which it is registered.
2. In a selective vending machine, a casing including an annular wall having its axis horizontally disposed, a vertical front wall adjacent said annular wall, a vertical rear wall spaced from said annular wall; a plurality of dividing walls projecting radially inwardly from said annular wall and providing a plurality of radially arranged article holding spaces, and a chute beginning between the rear wall and the annular wall and leading to an opening in said front wall, a push rod passing thru said front wall, a finger within said casing projecting radially from said rod; said finger being movable inwardly of the casing with said rod to pass thru any article holding space with which it is registered, and said rod being revoluble to selectively register said finger with any selected article holder.
3. In a selective vending machine a plurality of radially arranged article holders open front and rear, a revoluble push rod co-axial of said article holders, and a finger projecting from said rod movable thru any article holder with which it is registered.

In testimony whereof I affix my signature.

WILLIAM C. CUTLER.
